UNITED STATES PATENT OFFICE

WILLIAM B. STURGIS, OF CHICAGO, ILLINOIS

AUTOMATIC DRAFT REGULATOR

Application filed March 11, 1929. Serial No. 346,114.

The present invention relates generally to automatic draft regulating devices for maintaining a uniform or constant draft in the flue or outlet conduit of a heating apparatus by automatically regulating the entry of air into such flue in response to variations or fluctuations in the pressure of the escaping gases and products of combustion. More particularly the invention relates to that type of draft regulating device that embodies a counterbalanced damper plate or valve which is positioned adjacent to one end of a horizontally extending air inlet pipe and is mounted to swing on a fixed horizontal axis which is disposed eccentrically with respect to the damper plate and the air inlet pipe.

In regulator or damper devices of this character, the plate or valve is caused to be swung or tilted from its closed or vertical position whenever the upward flow of gases and products of combustion through the flue to the chimney creates in the air inlet pipe a sufficient suction or partial vacuum to overcome the action of the counterweight. This is attributable to the fact that one of the two parts of the damper plate at opposite sides of the axis of rotation is of greater area than the other part, and consequently responds to the differential pressures that exist inside and outside the inlet pipe. As the plate swings towards its fully opened or horizontal position, it is manifest that the active or suction responsive portion of the plate, that is, the portion that is in the larger of the two parts and is responsible for the tilting or valve opening action, gradually decreases in effective area. To cause the effective weight of the counterweight to diminish correspondingly in direct ratio or proportion to the suction responsive portion of the plate for the purpose of effecting and maintaining a uniform draft in the flue, it has heretofore been proposed to locate the counterweight on the distal end of a fixedly mounted rod which projects from one face of the plate and at right angles to the plane of the plate and is positioned in substantially intersecting relation with the axis of rotation. Whereas a counterweight arrangement of this character results in the damper plate operating effi-

ciently and accurately to maintain a uniform and constant draft in the flue between the heating apparatus and the chimney, it is impossible to effect, by shifting the counterweight longitudinally on the rod, and adjustment whereby the plate or valve is counterbalanced so that it responds or is tilted in response to a slight flow of air through the inlet pipe. In other words, with a counterweight arrangement of the type heretofore proposed, the range within which the damper plate may be adjusted for different draft intensities is exceedingly small and it is practically impossible to adjust the counterweight so that the plate is extraordinarily sensitive and is capable of being set to respond to minimum draft intensities in the flue.

One object of this invention is to improve upon dampers of the type and arrangement previously referred to by providing counterbalancing means whereby the range within which the damper plate may be adjusted for different draft intensities is materially increased and the damper plate is capable of being set or adjusted to maintain a minimum uniform draft in the flue. In general this counterbalancing means comprises a rod which extends through the axis of rotation and at right angles to the plane of the damper plate so that the effective weight thereof diminishes proportionately or correspondingly to the suction responsive portion of the damper plate during opening of the latter, and which projects outwardly from both faces of the plate and is mounted in place so that it may be shifted longitudinally in either direction for draft adjustment purposes. By shifting the rod bodily in one direction or the other, it is possible to counterweight variably the damper plate so that the latter operates to effect in the flue a uniform draft of substantially any desired intensity.

Another object of the invention is the provision of weights on the ends of the rod, which are individually movable lengthwise of the rod to effect a secondary adjustment of the counterweight means.

A further object of the invention is to provide an automatic draft regulator or damper

of the aforementioned character having means whereby the damper plate may be balanced to a nicety prior to the application or assemblage of the rod and counterweight means.

5 A still further object of the invention is to provide an improved damper which may be manufactured at a comparatively low cost and operates efficiently to maintain a constant or a uniform draft in the flue.

10 In addition, it is contemplated as one of the objects of the invention to provide an automatic draft regulator device which is an improvement upon that disclosed in Letters Patent of the United States No. 1,787,738, granted to me January 6, 1931.

15 Other objects of the invention and the various characteristics and advantages of the present construction will be apparent from a consideration of the following detailed description.

20 The invention consists in the several novel features hereinafter set forth and more particularly defined by the claims at the conclusion hereof.

25 In the drawings which accompany and form a part of this specification or disclosure and in which like numerals of reference denote corresponding parts throughout the several views:

30 Figure 1 is a vertical sectional view of a damper or automatic draft regulator embodying the invention, the damper plate or valve being shown in its vertical position, that is, the position that it assumes when not affected by a partial vacuum in the air inlet pipe;

35 Figure 2 is a front view;

40 Figure 3 is a perspective of the damper plate, illustrating in detail the pivot shaft and the balancing and counterbalancing means; and

45 Figure 4 is a detail sectional view of the collar which connects the rod and counterweights to the pivot shaft.

50 The device which forms the subject of the invention is operative to maintain automatically a uniform draft in the flue 10 of a heating apparatus, such, for example, as a furnace or heater fired by an oil burner. The flue 10 is adapted to convey upwardly the various gases and products of combustion and extends between the gas outlet for the combustion chamber and the chimney of the building with which the heating apparatus is associated. A horizontally extending air inlet pipe 11 is connected to one side of the flue 10 and is adapted to permit air to enter the interior of the flue to decrease the draft. In the drawing, the flue 10 and air inlet pipe 11 are shown in the nature of a T-shaped pipe section. The improved draft regulating device is adapted to control the passage of air through the inlet pipe 11 so as to maintain a substantially uniform draft in the flue 10. It 55 comprises a cylindrical sheet metal pipe sec-

tion 12, one end of which fits within the pipe 11. The said one end of the pipe section 12 is preferably crimped, as indicated in Figure 1 of the drawings, to permit it to be shifted readily into frictional engagement and sealed

70 relation with the pipe 11. An annular bead 13 is formed adjacent to the central portion of the pipe section 12 and forms a stop which operates to prevent the pipe section from being shifted too far into the pipe 11. The outer end of the pipe section is rolled or deflected backwardly around a wire hoop 14 for reenforcing purposes and to eliminate any exposed edges. The automatic draft regulating device, in addition to the pipe section 12, comprises a valve or damper plate 15

75 which is of circular conformation and such size as to close the passageway or conduit in said pipe section 12. This damper plate is preferably formed of sheet metal and has the marginal portion thereof bent inwardly to form a circumferentially continuous annular flange 16. A horizontal shaft 17 operates to form a pivotal support for the plate 15. The central portion of the shaft is soldered or otherwise rigidly secured to the inner face of the damper plate and the ends thereof project through circular apertures 18 in the flange 16 and are journalled in oppositely facing

80 holes 19 in the side portions of the pipe section 12. Spacing washers are mounted on the shaft 17 between the annular flange 16 and the portions of the pipe section 12 that form the holes 19. The shaft 17 is positioned beneath the center of the damper plate and the axis of the pipe section 12. By positioning the shaft in this manner, the damper

85 plate embodies more area or surface in the portion thereof above the pivot shaft than in the lower portion, and consequently is tilted into an angular position when unequal pressures exist inside and outside the pipe 12, that is, whenever the draft in the flue 10 creates a

90 partial vacuum in the air inlet pipe 11.

95 Figure 2 is a front view;

100 Figure 3 is a perspective of the damper plate, illustrating in detail the pivot shaft and the balancing and counterbalancing means; and

105 Figure 4 is a detail sectional view of the collar which connects the rod and counterweights to the pivot shaft.

110 The device which forms the subject of the invention is operative to maintain automatically a uniform draft in the flue 10 of a heating apparatus, such, for example, as a furnace or heater fired by an oil burner. The flue 10 is adapted to convey upwardly the various gases and products of combustion and extends between the gas outlet for the combustion chamber and the chimney of the building with which the heating apparatus is associated. A horizontally extending air inlet pipe 11 is connected to one side of the flue 10 and is adapted to permit air to enter the interior of the flue to decrease the draft. In the drawing, the flue 10 and air inlet pipe 11 are shown in the nature of a T-shaped pipe section. The improved draft regulating device is adapted to control the passage of air through the inlet pipe 11 so as to maintain a substantially uniform draft in the flue 10. It 115 comprises a cylindrical sheet metal pipe sec-

120 tion 12, one end of which fits within the pipe 11. The said one end of the pipe section 12 is preferably crimped, as indicated in Figure 1 of the drawings, to permit it to be shifted readily into frictional engagement and sealed

125 relation with the pipe 11. An annular bead 13 is formed adjacent to the central portion of the pipe section 12 and forms a stop which operates to prevent the pipe section from being shifted too far into the pipe 11. The outer end of the pipe section is rolled or deflected backwardly around a wire hoop 14 for reenforcing purposes and to eliminate any exposed edges. The automatic draft regulating device, in addition to the pipe section 12, comprises a valve or damper plate 15

130 which is of circular conformation and such size as to close the passageway or conduit in said pipe section 12. This damper plate is preferably formed of sheet metal and has the marginal portion thereof bent inwardly to form a circumferentially continuous annular flange 16. A horizontal shaft 17 operates to form a pivotal support for the plate 15. The central portion of the shaft is soldered or otherwise rigidly secured to the inner face of the damper plate and the ends thereof project through circular apertures 18 in the flange 16 and are journalled in oppositely facing

and is located slightly above the axis of rotation, as indicated in Figure 1. The plate is counterbalanced by means of a rod 24. This rod is mounted in a collar 25 which is rigidly secured to one end of the pivot shaft 17 by a set screw 26. The rod 24 is arranged to extend at right angles to the plane of the damper plate so that the effective weight thereof decreases in direct ratio or proportionally to the effective suction responsive area of the upper portion of the damper plate during opening of the latter. The collar 25 and the rod are connected together by a screw thread connection 27 which consists of a male thread on the rod and a female thread in the collar. By means of this screw thread connection, it is possible by rotating the rod, to shift the latter longitudinally or axially to effect the desired application of the counterweight. A characteristic and an advantage of the counterweight means set forth is that the range within which the damper plate may be adjusted for different draft intensities is a maximum in that it is possible to adjust the rod from a position wherein it practically balances the plate to a position wherein the effective weight is applied at a point remote from the axis of rotation. By adjusting the rod so that it substantially balances the damper plate, the latter is extremely sensitive to light currents of air passing through the air inlet pipe and consequently operates to effect in the flue 10 a uniform draft of minimum intensity. When the rod 24 is shifted outwardly with respect to the damper plate as far as possible, the effective weight thereof tends to increase the resistance of the damper plate to the flow of air through the pipe 11 and consequently the draft maintained within the flue 10 is of a materially greater intensity.

To permit of a minute or secondary adjustment of the counterweight means, a pair of weights 28 and 29 are provided. These weights are mounted on the ends of the rod 24 and have female screw threads formed therein, which cooperate with the male thread on the rod to enable the weights to be shifted longitudinally for adjustment purposes. By manipulating or shifting longitudinally the rod 24, it is possible to cause the damper plate to effect approximately in the flue 10, a uniform draft of a desired intensity. By rotating either of the weights 28 and 29, a secondary and more minute adjustment is obtained and it is possible to effect the exact desired draft intensity in the flue. The rod 24, together with the weights 28 and 29, exemplify counterbalancing means of an improved character.

In practice, it has been found that a more uniform and constant draft is obtained when the damper plate 15 is made to balance approximately, prior to the securing in place

of the rod 24 and the weights 28 and 29. With this in view, the end of the shaft 17, opposite the collar 25, is bent downwardly to form an element 30 which extends transversely to the axis of rotation and lies in the plane of the damper plate. A weight 32 is connected to the element 30 by a screw thread connection 31 so that it may be adjusted to and from the shaft 17. By adjusting the position of the weight 32, it is possible to have the damper plate properly balanced prior to the application or assemblage of the counterbalancing means. If the weight-member 20 proves not to be heavy enough to balance the plate properly, the counterweight 32 is adjusted downwardly until the desired balance is obtained. In addition to the function heretofore specified, the weight 32 and the element 30 permit of a ready adjustment in the event the use of a draft gauge discloses that the member 20 is not of the proper weight to effect the maintenance of a draft of uniform intensity. If a draft gauge shows that the draft in the flue 10 is not substantially uniform under all conditions, the weight 32 may be adjusted without the dismantlement of the regulator device proper until the desired draft uniformity is obtained.

When the automatic draft regulator is installed, the counterbalancing means is removed or disconnected with respect to the collar 25 so that the operative or individual effecting the installation may cause the damper plate 15 to be properly balanced by adjustment of the weight 32 relatively to the element 30. After the plate has been properly balanced, the pipe section 12 is shifted into its operative position with its crimped end in frictional engagement with the air inlet pipe 11. The rod 24 is then screwed through the collar 25, and the weights 28 and 29 applied to the ends thereof. To adjust the device for the desired draft intensity, the rod 24 is shifted longitudinally until approximately the proper counterbalancing of the damper plate is effected. The weights 28 and 29 are then manipulated to effect a final or secondary adjustment and to cause the damper plate to maintain in the flue 10 a uniform draft of the exact desired intensity.

In the operation of the device, the gases and products of combustion which emanate from the combustion chamber of the heating apparatus and pass upwardly through the flue 10 to the chimney, cause a partial vacuum to be produced in the air inlet pipe 11. When this partial vacuum or suction increases, due to the draft in the flue 10 becoming more intense than desired, the damper plate 15 automatically swings further towards its fully opened position to admit a greater quantity of air into the pipe 11. This additional supply of incoming air reduces the draft to

its normal intensity. As soon as the draft decreases, the suction in the air inlet pipe 11 also decreases thereby causing the damper plate to swing backwardly into its normal position. In the event that a change in the 5 intensity of the draft should be desired, the rod 24 or the weights 28 and 29 may be adjusted accordingly.

The damper or automatic draft regulator 10 herein disclosed consists essentially of but a small number of parts and consequently may be manufactured at a low and reasonable cost. It has proved in practice to be exceedingly efficient in operation due to the specific counterbalancing means explained, which means 15 permits the damper plate to be adjusted for different uniform draft intensities within a large range.

The invention is not to be understood as 20 restricted to the details set forth, since these may be modified within the scope of the appended claims, without departing from the spirit and scope of the invention.

Having thus described the invention, what 25 I claim as new and desire to secure by Letters Patent, is:

1. A damper device for automatically 30 maintaining a uniform or constant draft of a desired intensity in a flue, the combination of a casing having a passageway there- 35 through for introducing air into the flue, a plate for controlling the flow of air through the casing and into the flue, means forming a support whereby the plate is pivoted eccentrically so as to swing on an axis in the plane 40 of the plate, means for accurately balancing the plate about its axis of rotation comprising a weight-element mounted so that it is 45 movable bodily in the plane of the plate to- 50wards and away from the axis of rotation, and adjustable counterbalancing means for 55 the plate comprising an elongated arm ex- 60tending through the axis of rotation and pro- 65jecting outwardly relatively to both faces of the plate, said arm being mounted in place 70 so that it may be shifted longitudinally for counterbalancing purposes and being ar- 75ranged so that it extends horizontally when the plate is in its closed position in order that the leverage thereof upon the plate de- 80creases constantly as the damper opens.

2. In a damper device for automatically 85 maintaining a uniform or constant draft of a desired intensity in a flue, the combination of a casing having a passageway there- 90 through for introducing air into the flue, a plate for controlling the flow of air through the casing and into the flue, means forming a support whereby the plate is pivoted eccentrically so as to swing on an axis in the plane 95 of the plate, means for accurately balancing the plate about its axis of rotation comprising a weight-element mounted so that it is 100 movable bodily in the plane of said plate to- 105wards and away from the axis of rotation,

and adjustable counterbalancing means for the plate comprising an arm projecting radially with respect to the axis of rotation of the plate and a weight-element mounted on the arm so that it is movable bodily towards 110 and away from the axis of rotation for counterbalancing purposes, said arm being ar- 115ranged so that it extends horizontally when the plate is in its closed position in order that the combined leverage of the arm and the last mentioned weight-element upon the plate de- 120creases constantly as the damper opens.

3. In a damper device for automatically 125 maintaining a uniform or constant draft of a desired intensity in a flue, the combination of a casing having a passageway there- 130 through for introducing air into the flue, a plate for controlling the flow of air through the casing and into the flue, means forming a support whereby the plate is pivoted eccentrically so as to swing on an axis in the plane 135 of the plate, means for accurately balancing the plate about its axis of rotation comprising an arm disposed in the plane of the plate, and a weight-element mounted on the arm so that it is movable bodily in the plane of 140 the plate to and from the axis of rotation, and adjustable counterbalancing means for the plate comprising an arm projecting radially with respect to the axis of rotation 145 of the plate and a weight-element mounted on the arm so that it is movable bodily to- 150wards and away from the axis of rotation for counterbalancing purposes, said counterbalancing arm being arranged so that it extends horizontally when the plate is in its closed position in order that the combined leverage of the counterbalancing arm and the last mentioned weight-element upon the plate de- 155creases constantly as the damper opens.

4. In a damper device for automatically 160 maintaining a uniform or constant draft of a desired intensity in a flue, the combination of a casing having a horizontal passageway therethrough for introducing air into the flue, a plate for controlling the flow of air through the casing and into the flue, said plate being pivoted beneath its center so as to swing on a horizontal axis and being 165 adapted when in its vertical position, to close completely the passageway, means for accurately balancing the plate about its axis of 170 rotation comprising an arm extending down- 175wardly from the axis of rotation and dis- 180posed in the plane of the plate, and a weight- 185element mounted on the arm so that it is movable bodily in the plane of the plate to and from the axis of rotation, and adjustable counterbalancing means for the plate comprising an arm projecting radially with respect to the axis of rotation of the plate and a weight-element mounted on the arm so that it is movable bodily towards and away from the axis of rotation for counterbalancing 190 purposes, said counterbalancing arm extend-

ing at right angles to the plate so that it is truly horizontal when the plate is in its closed position and the combined leverage of the counterbalancing arm and the second mentioned weight-element decreases constantly as the plate swings into its open position.

5 5. In a damper device for automatically maintaining a uniform or constant draft of a desired intensity in a flue, the combination 10 of a pipe section for introducing air into the flue, a plate for controlling the flow of air through the passageway into said flue, a shaft connected fixedly to the plate and forming a pivotal support whereby the plate 15 is pivoted eccentrically and so as to swing on an axis that is substantially in the plane of the plate, means for accurately balancing the plate about its axis of rotation, comprising an elongated member connected to one end 20 of the shaft and projecting laterally therefrom in the plane of the plate and a weight mounted on and movable longitudinally of the arm, and adjustable means for counterbalancing the plate comprising an elongated 25 member projecting laterally from the other end of the shaft and extending at right angles to the plane of the plate and a weight mounted on and movable longitudinally of the member.

30 Signed at Chicago, Illinois, this 9th day of March, 1929.
